DESIGN.

H. C. BASCOM.

PARLOR STOVE.

No. 15,649.

Patented Dec. 30, 1884.

UNITED STATES PATENT OFFICE.

H. CLAY BASCOM, OF TROY, NEW YORK.

DESIGN FOR A PARLOR-STOVE.

SPECIFICATION forming part of Design No. 15,649, dated December 30, 1884.

Application filed October 20, 1884. Term of patent 7 years.

To all whom it may concern:

Be it known that I, H. CLAY BASCOM, a citizen of the United States, residing in the city of Troy, in the county of Rensselaer and State of New York, have invented and produced a new and original Design for Parlor-Stoves, of which the following is a specification, reference being had to the accompanying engraving of a stove having said design.

10 The urn shown on the cover of the stove is not a part of my present design.

This design embraces several new and distinctive parts and combinations of parts which go to make up the whole design, as hereinafter set forth.

One part of this design relates to the shape and ornamentation of the cover A, the same being of oblong quadrilateral form, and having the series of rectangular apertures a along its 20 upwardly and inwardly inclined lower portion, and the raised upper portion having the middle floral ornaments, b, the obliquely and laterally extending oblong apertures c, the obliquely and inwardly extending oblong end apertures, c', and the intervening triangular parts d. Another part relates to the shape and ornamentation of the two corner pilasters B, each having the flat front surface, e, with parallel upright edges, the capital f, and the 25 two oblong rectangular ornamented panels g, as shown.

Another complete distinctive part of this design is the ornamentation of the front plate, C, consisting of the laterally-extending branching compound vine, leaf, and floret ornament h, the row of radiating ornaments i, and the intervening semi-fan-form end ornaments connected by a beading, as shown. Another distinctive separate part is the shape and ornamentation of the forwardly-projecting fire-box casing E, consisting of the row of radiating ornaments m in the series of oblong panels, having contiguous parallel sides and rounded top and bottom ends, the row of knob ornaments n, and the ornamental end o, as shown.

Another integral part of this design is the shape and ornamentation of the forward base-extension consisting of the hearth-plate L and bottom extension-plate, K, each having their

forward corners and upper edges rounded, 50 and the intermediate upright plates embracing the door F, having the rectangular border p, the row of apertures p', with rounded tops and rectangular bottoms, and the intervening scale-bands q, capped by the ornaments q', and 55 the rectangular end panel, G, having the compound ornament r, consisting of a central rosette in a rectangular bead-frame, with outwardly-projecting lobe-form ornaments at the sides and corners. Another part is the shape 60 and ornamentation of the end plate, H, embracing the upper rectangular panel, s, having the compound floral ornament s', and the larger lower rectangular panel, t, having the compound floral ornament t'. 65

The design for the legs J consists of the convexly-curved surface x, having the curved beaded edges x', the compound floral ornament y, the contracted part z, and the foot z'.

The design for the stove consists of the 70 shape and ornamentation of the cover A, top plate, M, pilasters B, front plate, C, fire-box casing E, forward base-extension, L K F G, end plate, H, and legs J, substantially as shown, whether either of the doors D, having the parts j k l, or the skirting I, having the parts u v w w', shall or shall not be added.

I claim as new—

1. In a design for a stove, the shape and ornamentation of the open-work cover A, embracing the parts a b c c' d, as shown and described. 80

2. In a design for a stove, the shape and ornamentation of the pilasters B, embracing the parts e f g, as shown and described. 85

3. In a design for a stove, the ornamentation of the front plate, C, consisting of the compound ornament h, row of radiating ornaments i, and the intervening connected semi-fan-form ornaments, as shown and described. 90

4. In a design for a stove, the shape and ornamentation of the forwardly-projecting fire-box casing E, embracing the ornamental parts m, n, and o, as shown and described.

5. In a design for a stove, the shape and 95 ornamentation of the forward base-extension, embracing the parts L K F p p' q q' and G r, as shown and described.

6. In a design for a stove, the shape and ornamentation of the end plate, H, embracing the parts s s' and t t' , as shown and described.

7. In a design for a stove, the shape and ornamentation of the legs, consisting of the parts x x' , y , and z z' , as shown and described.

8. The design for a stove, embracing the parts A M B C E L F G H K J, shaped and ornamented substantially as described.

In testimony whereof I hereunto set my hand, in the presence of two subscribing witnesses, this 17th day of October, 1884.

H. CLAY BASCOM.

Witnesses:

CHARLES H. BENEDICT,
JAMES A. GILMAN.
